DESIGN FOR A COMBINATION SMOKING SET

Howard S. Long, Swissvale, Pa.

Application March 8, 1935, Serial No. 55,787

Term of patent 7 years

To all whom it may concern:

Be it known that I, Howard S. Long, a citizen of the United States, residing at Swissvale, in the county of Allegheny and State of Pennsylvania, have invented a new, original, and ornamental Design for Combination Smoking Sets, of which the following is a specification, reference being had to the accompanying drawing, forming part thereof. The figure is a perspective view of a combination smoking set, showing my new design.

I claim:

The ornamental design for a combination smoking set, as shown.

HOWARD S. LONG.
